United States Patent Office.

B. B. HILL, OF SPRINGFIELD, MASSACHUSETTS.

Letters Patent No. 95,344, dated September 28, 1869.

IMPROVED METHOD OF MANUFACTURING TYPE-WHEELS.

The Schedule referred to in these Letters Patent and making part of the same.

To all whom it may concern:

Be it known that I, B. B. HILL, of Springfield, in the county of Hampden, and State of Massachusetts, have invented a new and useful Improvement in the Manufacture of Type-Wheels; and I do hereby declare the following, when taken in connection with the accompanying drawings, and the letters of reference marked thereon, to be a full, clear, and exact description of said invention, and which said drawings constitute part of this specification, and represent, in—

Figure 1, a side elevation of my machine for forming the characters or figures upon a blank type-wheel;

Figure 2, an end elevation of the same;

Figure 3, a vertical longitudinal section, through line E F of fig. 2;

Figure 4, a side view of a type-wheel, with the characters formed thereon by my process; and in

Figure 5, a vertical section of the same, through line I K of fig. 4.

My invention relates to the process of forming the printing-characters upon the printing-face of type-wheels used in hand-stamps, and consists in confining the blank upon which the characters are to be made, firmly and securely between two clamps or plates, leaving a small portion around the periphery of the blank exposed to the action or operation of a die, having engraved or sunken figures or characters thereon, which die may be applied to the periphery of the blank, in a rotary manner, and both the die and the blanks may be made to revolve together, and under sufficient pressure, to cause the particles of metal near the rim to be forced or pressed more densely together, except such portions as enter the sunken characters, upon the die, to form the characters upon the periphery of the blank, while the main central portion of the blank being securely confined, is prevented from becoming enlarged in a direction parallel with its axis, or from changing its form or size.

That others skilled in the art may be able to practise my invention, I will proceed to describe the method I use for practising the same.

In the drawings—

A" represents two uprights or standards, in which operate two spindles, B and B', and upon the end of one spindle is an annular projection, a, having a shoulder at i, and upon the outer end, o, is made a screw-thread, upon which turns the threaded nut f.

If the blank has a hole therein, it may be placed upon the end o, and against the shoulder i, and the nut f is then turned up firmly against the blank e, or against the washer or plate e, placed between the

nut f and the blank, leaving the rim of the blank projecting a little beyond the projection a and plate e.

The nut f may be cylindrical, and the washer e dispensed with if desirable.

A cylindrical die, d, sufficiently hard, may be placed upon the other spindle B, and secured in place in the same manner as the blank is secured, said die having engraved or sunken characters thereon, and if one or both of the spindles are then made to revolve, while the die and blank are forced or pressed together, the periphery of the die will force back the metal at and near the periphery of the blank, except those portions which enter the sunken characters upon the periphery of the die, which portions will retain their original position, so that when the pressing or rolling is finished, the characters will be found projecting from the face or periphery of the blank.

Sometimes it may be desirable to use type-wheels which are solid, and have no hole therein. In such cases it is only necessary to place the blank against a plate, placing it in a right position, by means of a gauge, and bring another plate up against the other side of the blank firmly, so that the blank may be securely confined between and revolve with the two plates.

It will be seen that by thus confining or clamping the blank, but a very small portion of the metal of which it is composed is operated upon by the die, as all the main or central portion which is confined securely between the plates or clamps, cannot be acted upon, nor any of its particles displaced by the force of the die operating upon the surface of the blank, and the small amount of metal which is being operated upon at any one time, admits of the use of very light machinery in rolling the blanks.

It is evident that the die may be of any desirable form, either cylindrical and operating in a rotary manner, or it may be straight, and be made to perform a rectilinear reciprocating movement, as most desirable and convenient.

The small portion of metal near the periphery of the blank, which has been displaced, and which projects beyond the plane of its side, may then be removed by bringing up a cutting-tool against it, while the blank is still clamped in the machine and rotating, or it may be removed by placing it in a lathe, and then removing it by means of any of the common cutting-tools used for similar purposes, or in any other desirable and convenient way, and the type-wheel is then ready for use.

I am aware that blanks have heretofore been placed in dies, and then the whole blank expanded, either by heavy blows upon the flat side of the blank, or by driving an arbor, or spindle through a hole in the

centre of the blank, but in either of these processes all the particles of metal of which the blank is composed are displaced or acted upon, involving greater outlay in heavier tools, and in keeping the same in repair.

I am aware that the process of forming figures or characters upon metal, by means of a hardened metallic die, whether operating in a rotary manner, or otherwise, is not new in itself, and I do not claim the same independently of the feature of clamping or confining the metal to be operated upon, as herein described; and having, therefore, described my invention,

What I do claim as new, and desire to secure by Letters Patent, is—

1. As an improvement in the method of forming, by compression, the letters or figures on the periph-

ery of type-wheels, and to avoid thickening or displacement of the metal during such compression, except along the angles which separate the circumferential surface from the lateral surfaces, tightly compressing said wheel between two circular plates or disks, which completely cover and compress the two lateral surfaces of said wheel, excepting only a narrow rim or margin thereof, allowed for lateral extension under the action of the die, substantially as described.

2. As a new article of manufacture, a type-wheel, having characters or figures formed or produced upon its periphery by the process substantially as herein described.

B. B. HILL.
